(57) **CLAIM**

The ornamental design for a television receiver, as shown and described.

DESCRIPTION

1. Television receiver

1.1 : Perspective

1.2 : Front

1.3 : Back

1.4 : Left

1.5 : Right

1.6 : Top

1.7 : Bottom

1.8 : Reference

The present design is a television receiver in which a partial configuration can be customized according to user needs; the present design is characterized in that a system box on the rear surface of a panel is configured vertically since a film-type speaker is applied rather than an additional speaker module, thereby ensuring a neat wide rear surface and a slim panel; the present design can be used as metallic furniture or a partition dividing a space, since an article can be stored in a space on the rear surface the present design and at the
